International Search Report and Written Opinion issued for corresponding International Patent Application No. PCT/US2017/039126 dated Sep. 21, 2017.

Primary Examiner — Antoine Duval Davis(74) *Attorney, Agent, or Firm* — Stephen R. Valancius(57) **CLAIM**

The ornamental design for a hidden object detector, as shown and described.

DESCRIPTION

FIG. 1 is a front view of a hidden object detector showing our new design;

FIG. 2 is a rear view thereof;

FIG. 3 is a right side view thereof;

FIG. 4 is a top plan view thereof;

FIG. 5 is a bottom plan view thereof;

FIG. 6 is a perspective view thereof; and,

FIG. 7 is a left side view thereof.
